UNITED STATES PATENT OFFICE.

JOHN BARNES AND JACOB R. BARNES, OF GILMAN, ILLINOIS.

DESIGN FOR PHOTOGRAPH-PICTURE HOLDERS.

Specification forming part of Design No. **7,815**, dated November 3, 1874; application filed August 28, 1874.
[Term of Patent 14 years.]

To all whom it may concern:

Be it known that we, JOHN BARNES and JACOB R. BARNES, of Gilman, in the county of Iroquois and State of Illinois, have invented a new Improved Design for Photograph-Holder; and we do hereby declare that the following is a full, clear, and exact description of the same, reference being had to the accompanying drawing forming a part of this specification, in which the figure is a side elevation.

The invention relates to the form and outward aspect of photograph-holders; and consists in a novel design calculated to attract thereto, and produce a pleasing effect upon, the beholder.

It will first be described and then claimed.

A represents the photograph-holder, placed upon legs and having the usual panels; but each set, B B¹ B², arranged in a circle one

above another, diminishing in number upwardly, separated by curved and overlapping partitions C C¹ C² and capped by a ball.

We are aware that a revolving picture-stand having a series of superposed tiers diminishing in size upward and containing paneled sections, the whole resting upon legs and surmounted by an urn or vase is old, and we do not wish to be understood as making claim to such invention or design; but

What we do claim is—

The design for a photograph-holder, substantially as shown and described.

JOHN BARNES.
J. R. BARNES.
